A. GARDON

COLLAPSIBLE GRANARY

Filed Sept. 5, 1922

INVENTOR
Ambroise Gardon
BY *E. K. Bond*
ATTORNEY

UNITED STATES PATENT OFFICE.

AMBROISE GARDON, OF MEACHAM, SASKATCHEWAN, CANADA.

COLLAPSIBLE GRANARY.

Application filed September 5, 1922. Serial No. 586,299.

To all whom it may concern:

Be it known that I, AMBROISE GARDON, a citizen of the Dominion of Canada, and resident of Meacham, in the county of 5 Humboldt and Province of Saskatchewan, Dominion of Canada, have invented certain new and useful Improvements in Collapsible Granaries, of which the following is a specification.

10 This invention has relation to certain new and useful improvements in collapsible granaries and has for the primary object the provision of a granary which is simple in construction and comparatively inexpensive and may be readily set up or taken down and folded for transportation or 15 storage in collapsed condition.

The invention has for another object the provision of a collapsible granary, the body 20 or sides and top portions of which may be composed of canvas or the like with an opening in the top or cover portion which may be closed securely to prevent entrance of rain, the closure member being adapted 25 to be opened for airing the interior of the granary or for the purpose of placing grain therein or removing the grain.

A further object of the invention resides 30 in the provision of a granary of the character stated, which will include the canvas body and cover members and the supporting posts with the bracing or guy ropes and anchoring posts, ready for setting up 35 the granary as desired in any preferred location.

With the foregoing and other objects in view, as will appear as the description proceeds, the invention consists in the novel construction, combination and arrangement 40 of co-operating elements as hereinafter more specifically set forth, claimed and shown in the accompanying drawings forming a part of the present application in which:

Figure 1 is a plan view of the granary 45 constructed in accordance with the present invention, the guy ropes and anchoring posts being omitted from this view and the cover member being shown partially turned back.

Figure 2 is a vertical section through the 50 granary in set up condition, as indicated on line 2-2 of Figure 1 and looking in the direction indicated by the arrows.

Referring more in detail to the drawings, in which similar reference characters designate 55 corresponding parts throughout the several views, 3 indicates the body member

which is formed of a continuous strip of canvas or the like having bracing cords or bands 4 extending therearound. The body member 3 also has the upstanding body 60 supporting posts 5 arranged around its outer portion and connected thereto in a suitable manner. The posts 5 are provided with pointed extensions 6 at their lower ends in order that the posts 5 may be readily 65 secured in the ground to support the body member 3 of the granary in upright position, as shown in the drawings. The posts 5 also have reduced extensions 7 at their upper ends, over which the supporting or 70 guy ropes 8 may be engaged, the lower ends of the guy ropes being secured over the anchor posts 9 driven at an angle into the ground around the body members 3 and outwardly of the posts 5, as shown clearly in 75 Figure 2. The body member 3, when set up as shown in the drawings, will form the body or sides of a cylindrical granary structure, with the lower edge of the body 3 bearing upon the supporting surface to prevent 80 water from working under the body member 3.

The granary structure is completed by a conical top or roof member 10 secured at its lower edge to the upper edge of the body 85 member 3 in any suitable and well known manner to form a water-tight and air-tight connection between the members 3 and 10. This top or roof member 10 should also be formed of canvas or some other water-proof 90 material. A centre post 11 is employed to support the top or roof member 10 of the granary structure in proper position. This centre post 11 is provided with a reduced lower end 12 adapted to be driven into the 95 ground, while a reduced upper end extension 13 of the post 11 is extended through an opening 14 provided therefor in the apex of the top or roof member 10.

The top or roof member 10 is shown in 100 Figure 1 as being composed of sections of segmental form connected together with their pointed ends meeting at the apex of the top or roof member 10. These sections are designated by the numeral 15. One of the sections 15 is considerably larger than the remaining sections and has the openings 16 formed therein with a reinforcing strip 17 secured around the edges thereof. A closure member 18 is permanently secured 105 along one edge of the opening 16, as shown at 19. The remaining edges 20 and 21 of

the closure member 18 are adapted to be secured in closed position along the corresponding re-inforced edges of the opening 16 by suitable securing members, as indicated 5 in the drawings.

It is believed that the complete construction of the granary may now be readily understood from the foregoing paragraphs taken in connection with the accompanying 10 drawings without further detailed description. It may be briefly stated, however, that the granary may be readily set up or taken down as desired. Furthermore, the closure member 17 may be opened for the 15 purpose of placing grain within the granary, removing grain therefrom or for airing and ventilating the granary. The closure member 18 may be readily secured in closed position with its edges overlapping the re-inforced edges of the opening 16 in the top or roof member 10 to form a water-tight 20 closure and prevent rain from entering the granary.

While the preferred embodiment of the

invention has been disclosed, it is to be 25 understood that minor changes in the details of construction and arrangement of parts may be resorted to within the scope of what is claimed without departing from the spirit of the invention.

What I claim as new is:

A collapsible granary comprising a flexible water-proof body member, said body member being re-inforced and continuous, supporting posts arranged upon said body member, means for anchoring said posts in upstanding position, said posts having reduced end portions, a flexible water-proof roof member connected with said body member, said roof member having an opening 35 formed therein and re-inforced around its edges, a cover member carried at one edge of said opening and adapted to be secured along the remaining edges thereof and a centre post for said roof member.

In testimony whereof, I affix my signature.

AMBROISE GARDON.
